[57] **ABSTRACT**

A sequential switch is composed of a plurality of ganged multi-contact switch pairs connected in series, a current path being established to operate a lock when a switch of each pair is set to the correct contact. In a second embodiment, a variable digit sequential switch, the ganged pairs are connected so that a switch of an even number of pairs must be set to the correct contact to close the current path.

SEQUENTIAL SWITCH ARRANGEMENTS FOR OPERATING ELECTRICALLY CONTROLLED LOCKS

BACKGROUND OF THE INVENTION

The invention relates to electrically operated locks for safes and vaults.

The prior art contains a number of sequential locks that are operated without a key. These known sequential locks, however, because they are purely mechanical in operation, can be opened by a clever burglar.

SUMMARY OF THE INVENTION

An object of the invention is a sequential switch lock that can be opened only by knowing its code.

Another object of the invention is a variable digit sequential switch that has a very large number of possible codes for a relatively small number of ganged switch pairs.

The invention consists essentially of at least one pair of multicontact switch means, each switch means having a set of contacts, conductor means connecting a selected contact of one switch means to a selected contact of the other switch means of said pair; movable means comprised by each said switch means for contacting each contact of said set to make an electrical connection between said movable means and each contact, and a circuit including lock operating means, said circuit being electrically connected to said movable means, whereby when said movable means of both said switch means are in electrical contact with the respective selected contacts said circuit is closed.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is a schematic plan view of a switch suitable for use with the invention;

FIG. 2 is a schematic plan view of two interconnected switches;

FIG. 3 schematically shows a sequential switch of the invention;

FIGS. 4 and 5 are diagrams of circuits, using a sequential switch of the invention, for operating the lock of a safe;

FIG. 6 is a wiring diagram of a circuit suitable for a house or hotel room;

FIG. 7 is a wiring diagram of a vehicle ignition lock arrangement;

FIG. 8 is a detail of the mechanical construction of the embodiment shown in FIG. 7;

FIG. 9 is a wiring diagram of a variable digit sequential switch of the invention;

FIGS. 10 and 11 are isometric views of a safe incorporating a variable digit sequential switch;

FIG. 12 is a detail of the mechanical construction of the lock of the safe; and

FIG. 13 is a diagram of a circuit suitable for the safe shown in FIGS. 10 and 11.

DESCRIPTION OF THE PREFERRED EMBODIMENTS

The switch, or dial, of a sequential switch is composed of an even number of contacts. The number of switches in the embodiment of FIG. 2 can be even or odd. The structure of a dial is shown schematically in FIGS. 1 and 2.

A switch is made of electrically insulating material 10 divided into a stator and a rotor, as shown in FIG. 1, wherein A denotes the second member or stator and B the first member or rotor. The inner face of the stator ring has embedded therein 10 metal contacts *d*, numbered from 0 to 9. A wiper *c* is shown on rotor B.

15 When the rotor turns about the central axis, wiper *c* contacts successive ones of the contacts *d*. A wire *a* is connected to the wiper *c*. FIG. 1 shows a respective wire *l₀* to *l₉* connected to the corresponding contact 0 to 9.

20 Two switches connected together so that a contact wire of one is connected to a corresponding contact on the other dial are called ganged switches, or dials. The term ganged as herein used does not mean that the rotors of two or more switches are mechanically coupled together. A current path is formed only when both rotors of two ganged switches are rotated to the same corresponding contact *d*: in other words, when the rotor of one switch is rotated to contact 3 and the rotor of the other switch is also rotated to the contact 3. FIG. 2 shows a pair of ganged switches, having wiper wires *a* and *b*. The two switches of the pair will be electrically connected together when both wipers contact the respective contacts 5 of their stators, in the particular example shown.

25 FIG. 3 schematically shows a sequential switch composed of four pairs of ganged dials, X₁ and Y₁, X₂ and Y₂, X₃ and Y₃, X₄ and Y₄. Only when X₁=Y₁, X₂=Y₂, X₃=Y₃, and X₄=Y₄ simultaneously is there a current path from *a* to *b*. This means, for example, that contact 1 of X₁ is connected to contact 1 of Y₁, contact 5 of X₂ is connected to contact 5 of Y₂, contact 3 of X₃ is connected to contact 3 of Y₃, and contact 7 of X₄ is connected to contact 7 of Y₄. Only one corresponding contact *d* of a pair of ganged switches is connected together. Therefore, each switch of a ganged pair must be set to the right number. Any inequality caused when two switches of a ganged pair are not set to the same correct number will result in an open circuit between *a* and *b*. If the switches Y₁, Y₂, Y₃ and Y₄ are mounted 30 inside a safe with the switches X₁, X₂, X₃, and X₄ accessible from the outside, and the latter rotated until the four equalities are satisfied in order that *a* and *b* are connected together, then the safe can be opened. This will be explained in detail. The connection between each ganged pair is made to the user's liking, and the sequential switch can be extended to include more than 35 four ganged pairs.

40 This switch can be utilized to control an electromagnet, which in turn controls the movement of a lock for the safe.

The sequential switch of the invention virtually ensures that the safe cannot be opened by someone not privy to the correct setting of each ganged pair.

45 For convenience, point *a* will be considered the "input" of the sequential switch, and point *b* the "output".

FIG. 4 shows a simple circuit to operate an electromagnet L₁, which latter controls the lock of a safe. The

box 10 denotes a sequential switch of the kind described in connection with FIGS. 1, 2 and 3. The power supply can be either a.c. or d.c., the supply being hidden inside the safe. K₁ is a pushbutton switch. When a and b are connected together by the appropriate turning of the deals, L₁ will be energized as soon as K₁ is pushed. Once L₁ is energized, 12, which is a switch controlled by L₁, will be closed. L₁ will retain its attractive force even after switch K₁ is released, because 12 and K₂ are closed. To lock the safe one need only to open K₂ and to turn the dials randomly.

The embodiment shown in FIG. 5 is similar to the embodiment shown in FIG. 4, but with an added alarm. Parts having the same function as in the previous form of the invention are denoted by the same reference numerals. The alarm operates on 3 volts d.c., 13 being one coil of this alarm, and 14 being the other, wound in the opposite direction relative to 13. If a and b are connected together, pressing K₁ will magnetize L₁, exciting 13 and 14. The lock then opens, but the bell 17 will not ring because 13 and 14 are wound in opposite directions. If K₁ is pressed with a and b open, only 13 is energized. The alarm will sound. A thief must succeed on the first try or else the alarm will give warning. Resistors 15 and 16 are inserted to drop the voltage to 3 volts for 13 and 14. T₁ and T₂ are rectifiers. Their purpose is as follows. When 13 rings the alarm, the fluctuating current in 13 will induce a back EMF across the terminals of 14. T₁ and T₂ block this voltage from reaching L₁ so that the safe cannot be opened accidentally. More complex circuits can be designed. The one shown here is only offered as an example of an application of the sequential switch.

The embodiment shown in FIG. 6 shows the sequential switch of the invention as applied to a private house or a hotel room to prevent the entry of a burglar. Fundamentally, it operates in the same way as the embodiment of FIG. 5. In addition to the components of the circuit shown in FIG. 5, the embodiment of FIG. 6 has a triple-pole push-button indoor switch 24, an indoor locking switch 23, an outdoor locking switch 22, and a switch 18. The sequential switch is denoted by the box 10. When the owner wants to go out he presses 24, and coils L₁, 13, and 14 are excited simultaneously. The lock, which is operated by L₁, is opened, and the alarm 17 is not actuated. 12 and 18 are closed by the magnetization of L₁. Hence, if 24 is released, current will continue to flow through L₁. The reason that a triple-pole switch is used for 24 is that the instant that 19, 20 and 21 are connected, current will pass through 14. Switch 12 does not close until L₁ is energized by the closing of 19, 20 and 21.

Unless current flows through L₁, 13, and 14 at the same time, the alarm 17 will sound. This is avoided by connecting 19, 20 and 21 simultaneously. The owner can lock indoors by pressing 23 and lock outdoors by pressing 22.

The switch 18 is also useful in that when the owner enters, he can turn the dials of 10 at random so that a steady current is maintained in L₁ through switch 12 and switch 18, the latter shunting the sequential switch 10, the dials of which are randomly turned.

The embodiment shown in FIGS. 7 and 8 illustrates a circuit to control the closing of the ignition circuit of a motor vehicle, such as a taxi.

L₁ is used to attract the plunger which is fabricated as the lock inside the hood of the vehicles. Thieves are

unable to open the hood and connect the circuit leading to the spark plugs directly. When L₁ attracts the plunger, the hood is unlocked.

The sequential switch 10 is installed in a box 28 next to the steering wheel and near to the dashboard of the automobile. Switches 27 and 28 are placed in the box. The lock on the box is controlled by electromagnet 29. When 29 is energized, the box is unlocked.

With reference to FIG. 8, an electrically insulated cylinder 31 is drilled with a rectangular key hole 34. A protruding metal block 32 is shown on the cylinder. A spring is hidden inside 32 so that it is urged in the direction of arrow E. The driver, after entering the vehicle, moves the dials on the sequential switch 10 to establish an electrical path between points a and b. Then he closes switch 27 and proceeds in the manner as will be explained. Once the vehicle is started, the driver again moves the dials of 10 to open the path between a and b.

An iron bar 33 is under the control of electromagnet 30, and is attracted in the direction of arrow B when 30 is excited. Turning cylinder 31 in the direction of the arrow D will cause the metal block 32 to contact a metal contact (not shown) and an electric path is formed.

After a and b are connected and 27 closed, the circuit of the automobile is connected by the procedure just described. As soon as the circuit is made, the dials are turned so that the electromagnet 30 is deenergized. The bar 33 returns to its original position. The circuit is open if the cylinder 31 is rotated in a direction opposite to that of arrow D. The metal block 32 will be disconnected from the aforesaid metal contact and the ignition is opened. Even though the bar 33 is returned to its original position, the block 32 can still compress in the E direction.

L₁ and 29 control 26 and 25, respectively. When L₁ and 29 are energized, 26 and 25 are closed. They operate similarly to switch 18 in the embodiment shown in FIG. 6.

There will now be described the operation and construction of the variable-digit sequential switch.

With reference to FIG. 9, B₁, B₂, . . . , B₁₀ are ganged switches, or dials. A₁, A₂, . . . , A₉ are electromagnets composed of two windings with the same turns wound in opposite direction. Electromagnet A₁ governs the movement of d₁ only, which latter is a thin metal spring, whereas A₂ governs d₂ and d₂', A₃ governs d₃ and d₃', and so forth. The position of the spring d₁ is controlled by electromagnet A₁.

For the sake of convenience, the points P and Q will be considered respectively the "input" and the "output" of the variable digit sequential switch.

When A₁ is energized, contact is made between d₁ and c₁. When A₁ is not energized, d₁ is connected with b₁.

When A_i (where i = 2 to 9) is energized, contact is made between d_i and c_i, and between d_i' and c_i'. When A_i is not energized, d_i contacts b_i, and d_i' contacts b_i'.

Switches a₁¹, a₁², a₁³ are assembled on a common shaft, so that when a₁¹, a₁² are closed, a₁³ is open. These three switches constitute a selector called D₁.

a₁₀¹ and a₁₀² are assembled on selector D₁₀. Unless D₁₀ is turned, switch a₁₀¹ remains closed and switch a₁₀² remains open. If selector D₁₀ is turned, then a₁₀¹ is opened and a₁₀² is closed.

Similar reasoning applies to a_1^1, a_1^2, a_1^3 , and a_1^4 (where $i = 2$ through 9). Unless selector D_i (where $i = 2, \dots, 9$) is turned, a_1^1, a_1^2, a_1^3 remain closed and a_1^4 is open. When D_i is turned sufficiently, the above switch connections are reversed.

Once we choose an even number of selectors from all D_i 's (where i now = 1, ..., 10) and turn them, what will happen? The following illustration provides the answer.

If D_1, D_4, D_8 and D_{10} are moved from their neutral position and X_1, X_4, X_8 and X_{10} are set equal to Y_1, Y_4, Y_8 and Y_{10} , a conductive path is established between P and Q, as will be explained, step by step.

Having turned D_1, D_4, D_8 and D_{10} from their neutral position, $a_1^1, a_1^2, a_4^1, a_4^2, a_4^3, a_8^1, a_8^2, a_8^4, a_{10}^1$ are opened, but $a_1^3, a_4^3, a_8^3, a_{10}^2$ are closed.

Since $D_2, D_3, D_5, D_6, D_7, D_9$ remain unchanged in their position, $a_2^1, a_2^2, a_2^4, a_3^1, a_3^2, a_3^4, a_5^1, a_5^2, a_5^4, a_6^1, a_6^2, a_6^4, a_7^1, a_7^2, a_7^4, a_9^1, a_9^2$, and a_9^4 remain closed, while $a_2^3, a_3^3, a_5^3, a_6^3, a_7^3$, and a_9^3 , remain open.

Therefore, the following switches are closed: $a_1^3, a_2^1, a_2^2, a_2^4, a_3^1, a_3^2, a_3^4, a_4^1, a_5^1, a_5^2, a_5^4, a_6^1, a_6^2, a_6^4, a_7^1, a_7^2, a_7^4, a_8^1, a_8^2, a_8^4, a_{10}^1$.

The following switches are open: $a_1^1, a_1^2, a_2^3, a_3^3, a_4^1, a_4^2, a_5^3, a_6^3, a_7^3, a_8^1, a_8^2, a_8^4, a_9^3$, and a_{10}^1 .

It is assumed in FIG. 9 that current flows from negative to positive. As soon as the switch K is closed, current flows from K to P, through L_1 to r_1 , and to the positive pole of the power supply 11. No current flows through L_1^1 , since a_1^1 is open. Therefore, electromagnet A is energized. Spring d_1 , attracted by A₁, contacts c_1 , so that no current flows through b_1 ; therefore, no current flows through L_2 and L_2^1 of A₂¹. a_1^2 is open and a_1^3 is closed. Part of the current flows through L_1 , while the other part flows through the path c_1 to d_1 to a_1^3 , and through ganged dials B_1 to b_2 . Neither L_2 or L_2^1 of A₂ is energized, so d_2 and d_2' will not be attracted by A₂, and d_2 contacts b_2 , and d_2' contacts b_2' . Current reaching b_2' flows along the path a_2^4 to b_3' to a_3^4 to b_4' . Current also flows along the path b_4' to B₄ to a_4^3 to b_4 , since a_4^4 is open and a_4^3 is closed. Consequently, no current flows through the coils of A₂, A₃, and A₄. d_3 remains in contact with b_3 , d_3' with b_3' , d_4 with b_4 , and d_4' with b_4' .

Since A₄ is unenergized, current reaching a_4^3 follows two paths: a first path consisting of b_4 to L_5' to a_5^1 to r_{10} ; and a second path consisting of b_4 to L_5 to r_9 . Both of these paths end at the positive pole of the supply 11. Current in both L_5 and L_5' produces cancelling fields, making A₅ passive and leaving d_5 in contact with b_5 , and d_5' in contact with b_5' .

There is also another path from the connection b_4 , in addition to the two just described. This other path is b_4 to a_5^2 to b_5 . At this point the path has two branches, a first consisting of path L_6 to a_6^1 to r_{12} to supply 11; and a second, consisting of L_6 to r_{11} to supply 11. Current in both L_6 and L_6' render A₆ passive, so that d_6 and b_6 are connected and d_6' and b_6' are connected.

Current at b_6 flows to a_6^2 to b_6 from where it separates into two branches, a first branch consisting of L_7 to a_7^1 to r_{14} to source 11, and a second branch consisting of L_7 to r_{13} to 11. As a consequence of current flowing through both windings, d_7 remains in contact with b_7 , and d_7' remains in contact with b_7' .

Current passing through b_6 will also follow a second path: b_6 to a_7^2 to b_7 to L_8 to r_{15} to 11. A₈ is energized, and d_8 and d_8' are respectively disconnected from b_8 and b_8' and connected to c_8 and c_8' .

Since d_8 is disconnected from b_8 , A₈ is unenergized, and d_9 remains in contact with b_9 and d_9' in contact with b_9' .

At connection b_7 the current takes two paths, a first consisting of b_7 to c_8 to a_8^3 and through B₈ to c_8' , and a second consisting of b_7 to b_9' to a_9^4 and through B₁₀ to a_{10}^2 . d_8 is connected with c_8' , and a_8^2 is open.

Since a_{10}^1 is open, A₉ is not energized, and d_9 remains in contact with b_9 and d_9' in contact with b_9' .

Current passing through the ganged pair B₁₀ returns to the supply 11 through Q and the load L. Thus, there is formed a closed path.

A closed path between P and Q is made if any even-number of selectors are turned. What is illustrated above is only an example. Usually the power supply will be d.c. The polarity of the battery can be reversed. An a.c. source can be used if there are taken into consideration the frequency of the a.c. source, the attraction of A₁, A₂, ..., A₉, and the restoring force of d₁, d_{1'}, d₂, ..., d₉, d_{9'} which are governed by A₁, A₂, ..., A₉.

The resistors r_i ($i = 1, 2, \dots, 18$) are used because the voltage rating of the coils is small. The series connection of these resistors shares a portion of the voltage. If the coils of A_i are properly designed, r_i can be discarded.

When mounting this variable-digit sequential switch in a safe with the X dials (contained within the broken line box in FIG. 9) it is not necessary to use all of the dials. As shown in the above example, if $X_1=Y_1, X_4=Y_4, X_8=Y_8$, and $X_{10}=Y_{10}$, then a closed path is made. Any even number of selectors D_i and of the corresponding ganged dials B_i is suitable.

The total possible combinations of this arrangement are $C_2^{10} \times 10^2 + C_4^{10} \times 10^4 + C_6^{10} \times 10^6 + C_8^{10} \times 10^8 + C_{10}^{10} \times 10^{10} = 14$ billion. The variable digit sequential switch of the invention is suitable for all safes and vaults in which valuables are kept.

For example, if we let $X_1=Y_1=3, X_4=Y_4=1, X_8=Y_8=7$, and $X_{10}=Y_{10}=0$, the code is 3170. D₁, D₄, D₈ and D₁₀ are turned from their normal position beforehand. The X₁, X₄, X₈ and X₁₀ dials are set to their correct positions. K is then closed, and the lock is opened. Only the X dials, the switch K, and the power supply plug and socket are exposed. Everything else is inside the safe or vault.

With reference to FIGS. 10 and 11, there is shown the way in which the variable digit sequential switch of the invention is built into a large safe 35 having a central partition 53. The safe could also be a vault. The safe has two doors 36 and 37 with respective handles 38 and 39. The reference numerals 40, 41, and 42 respectively denote the master opening switch, the switch for opening door 36, and the switch for opening door 37, as will be made clear in connection with FIG. 13. Ten exposed dials 43, five in each door, are rotatably mounted in the boxes 44 and 45 secured to the inside of the safe doors. The rotatable vertical shafts 46 of these dials are drivingly connected to corresponding dials completely hidden from view in the boxes 47 and 48, also secured to the inside of the respective doors 36 and 37. These latter, hidden, dials correspond to the dials X₁, ..., X₁₀ shown within the broken-line box in FIG. 9. The 10 dials 49 (only four are shown), projecting from the boxes 50, correspond to the dials Y in FIG. 9 and are exposed when the safe is open to permit the code to be changed at will, since only those Y dials are correctly set that correspond to the code chosen. In the

example previously given, the Y dials 1, 4, 8, and 10 are respectively set to the numbers 3, 1, 7, and 0, but the remaining Y dials are not correctly set.

The two metal boxes 51, which are spot welded, or otherwise fixed, to the doors 36 and 37, each house the lock mechanism for the respective door, and the electromagnet for operating the lock.

The nine electromagnets A₁, . . . , A₉ of FIG. 9 are held underneath the safe floor 52.

The selectors D₁ to D₁₀, previously described in connection with FIG. 9, are mounted at the base of the safe, and are exposed when the safe is open. Only those selectors are turned beforehand that correspond to the ganged dial pairs of the code.

The selectors D are always mounted inside of the safe, whereas either the dials X or the dials Y (but not both!) can be the dials that are operated from outside of the safe by turning the exposed dials 43.

Each lock mechanism, one of which is shown in FIG. 12, operates respective vertical door locking rods 54 and 55, and a horizontal locking rod 56. The respective door handle 38 or 39 can turn a cam 57 clockwise, to lock, and counterclockwise, to open, the door. Assuming that the safe is to be locked up, the cam 57 is turned clockwise, in the direction of the arrow, pushing the vertical rods 54 and 55 respectively up and down, as shown by the arrows, and the horizontal rod 56 to the left. The springs 58 urge these rods against the lobes of the cam 57.

The cam incorporates a pole 60 that accepts a spring biased bolt 59 that is normally urged to enter the hole 60. This bolt is controlled by a respective one of the electromagnets 61 or 62, shown in FIG. 13. When the hole 60 is aligned with the withdrawn bolt 59, the controlling electromagnet 61 or 62 is turned off, causing the spring biased bolt 59 to shoot into the hole 60, thereby locking the door handle. The locking bar 54, 55, 56 have previously been moved to their locking positions by the rotation of the cam 57.

FIG. 13 shows a circuit, broadly similar to those shown in FIGS. 5 and 6, suitable for the safe just described. The variable digit sequential switch, shown in FIG. 9, is denoted by 63. The points P, Q, and m are the same as the similarly referenced points in FIG. 9. Those components having the same function as in the circuits of FIGS. 5 and 6 are denoted by the reference numerals of these latter Figures.

The safe door mounted switches 40, 41, and 42 are bridged by respective switches 65, 66, and 67, which are respectively controlled by the electromagnets 64, 61, and 62 and closed when the latter are energized. A switch 68, operated to close by the electromagnet 64 when the latter is energized, shunts the variable digit sequential switch 63.

A push button switch 69 is provided for locking the safe. The circuit also comprises an alarm 17 and the two diodes T₁ and T₂. The electromagnets 61 and 62, as previously explained, operate the bolt 59 of a respective door 36 or 37. Each electromagnet 61 and 62 is advantageously held in the box 51 of a respective door.

If only door 36 is to be opened, first switch 40 and then switch 41 are pressed. If only door 37 is to be opened, first switch 40 and then switch 42 are pressed.

It will be understood that each of the elements described above, or two or more together, may also find a useful application in other types of circuits and constructions differing from the types described above.

While the invention has been illustrated and described as embodied in sequential switch arrangements for operating electrically controlled locks, it is not intended to be limited to the details shown, since various modifications and structural changes may be made without departing in any way from the spirit of the present invention.

Without further analysis, the foregoing will so fully reveal the gist of the present invention that others can 10 by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims:

1. Switch arrangement for use in electrical combination locks, comprising in combination a pair of multi-position switches settable independently of each other, each including a first member having a first electrical contact thereon, and a second member having a plurality of second electrical contacts thereon, one of said members of each switch being movable relative to the other of said members of the same switch in a sense effecting electrical connection between said first contact and any of said second contacts; connecting means for electrically connecting at least a predetermined one of 20 said second contacts of one of said switches to a predetermined one of said second contacts of the other of said switches, whereby a current path between said first contacts is formed only when said first contacts are electrically connected with said predetermined ones of 30 said second contacts; electrical lock-operating means connected in circuit with said first contacts, and including electromagnet means, first normally open switch means connected in series with said electromagnet means and with said first contacts, second normally 35 closed switch means connected in series with said electromagnet means and said first contacts, and normally open third switch means shunted across said first switch means and closed by said electromagnet means when the latter is energized; alarm means for generating an 40 alarm signal upon closing of said first switch means when said first contacts are not electrically connected with said predetermined ones of said second contacts and including first and second coils wound in opposing 45 senses and circuit means connecting said coils with said switches and with said lock-operating means for effecting energization of both of said coils when said first switch means is closed and said first contacts are connected with said predetermined contacts, and for 50 effecting energization of only one of said coils when said first switch means is closed and said first contacts are not connected with said predetermined contacts.

2. An arrangement as defined in claim 1, including diode means connected to prevent a voltage induced in the other of said first and second coils from reaching 55 said electromagnet means when only said one coil is energized.

3. An arrangement as defined in claim 21, one of said first contacts constituting an input and an other of said first contacts defining an output, and wherein said circuit means includes current source means; normally open fourth switch means connected in series with said first and second switch means, said first, second and 60 65

fourth switch means being connected between one side of said current source and said output; normally open fifth switch means connected between said input and said output and operated by said electromagnet means to close when the latter is energized; normally open triple-pole switch means having two poles respectively connected to said input and output and a remaining pole connected to one side of said current source means.

4. Switch arrangement for use in electrical combination locks, comprising in combination at least three pairs of multi-position switches, the switches of each pair being settable independently of each other, and each switch including a first member having a first electrical contact thereon and a second member having a plurality of second electrical contacts thereon, one of said members of each switch being movable relative to the other of said members of the same switch in a sense effecting electrical connection between said first contact and any of said second contacts; connecting means for electrically connecting at least a predetermined one of said second contacts of one of the switches of each pair to a predetermined one of said second contacts of the other of the switches of the same pair, whereby a current path between said first contacts is formed only when said first contacts are electrically connected with the respective ones of said predetermined second contacts, and including additional connecting means for connecting said first contacts in series; electrical lock-operating means connected in circuit with the series connection of said first contacts, with the first contact of one of said switches constituting an input and the first contact of an other of said switches constituting an output; and further including a discrete first electromagnet associated with each of said pairs except that pair at said output, each said first electromagnet having a passive and an active state; a discrete first switch means operated by each said first electromagnet to move from a first to a second position when said first electromagnet is active; and a discrete second switch means connected to each of said pairs and having first and second positions, whereby in said second position

said first electromagnet associated with the pair to which said second switch means is connected is active provided that said movable means of the immediately preceding pair in the direction of said input is in contact with the respective selected contacts, said first and second switch means cooperating so that when said second switch means is in said second position the associated pair is connected in said circuit provided that the movable means of said pair is in contact with the respective selected contacts.

5. An arrangement as defined in claim 4, as used to operate the lock of a safe or vault, wherein said lock operating means is a second electromagnet, and further including current source means; normally open third switch means connected in series with said second electromagnet, said second electromagnet and third switch means being connected between one side of said current source means and said output, the other side of said current source means being connected to said input.

10 6. An arrangement as defined in claim 5, further including normally open fourth switch means connected across said third switch means and operated by said second electromagnet to close when the latter is energized.

15 7. An arrangement as defined in claim 6, further including normally open fifth switch means connected between said input and said other side of said current source means.

20 8. An arrangement as defined in claim 7, further including normally open sixth switch means connected across said fifth switch means; and a third electromagnet connected in parallel with said series connected second electromagnet and third switch means for operating said sixth switch means to close the latter when said third electromagnet is energized.

25 9. An arrangement as defined in claim 8, further including normally open seventh switch means connected between said input and output and operated by said third electromagnet to close when the latter is energized.
